UNITED STATES PATENT OFFICE.

LUCIUS M. TYNES, OF GLOSTER, MISSISSIPPI.

ATTACHMENT FOR SEWING-MACHINES.

1,227,980.

Specification of Letters Patent. Patented May 29, 1917.

Application filed June 19, 1915. Serial No. 35,035.

To all whom it may concern:

Be it known that I, LUCIUS M. TYNES, a citizen of the United States, residing at Gloster, in the county of Amite and State of Mississippi, have invented a new and useful Attachment for Sewing-Machines, of which the following is a specification.

The device forming the subject matter of this application is an attachment adapted to 10 be assembled with the needle and the needle bar of a sewing machine, for carrying out embroidery work, the structure being of peculiar utility for use in connection with embroidery hoops.

15 It is one object of the invention to provide a structure of the sort above mentioned which may be operated readily in connection with embroidery hoops.

Another object of the invention is so to 20 construct the device that the work will be guided smoothly thereunder without catching.

Another object of the invention is to provide a structure of this sort in which the 25 work is exposed to view, to a maximum extent.

It is within the province of the disclosure to improve generally and to enhance the utility of devices of that type to which the present 30 invention appertains.

With the above and other objects in view which will appear as the description proceeds, the invention resides in the combination and arrangement of parts and in the 35 details of construction hereinafter described and claimed, it being understood that changes in the precise embodiment of the invention herein disclosed can be made within the scope of what is claimed, without departing 40 from the spirit of the invention.

In the accompanying drawing:—

Figure 1 shows the invention in perspective, applied to a portion of a sewing machine;

45 Fig. 2 is a bottom plan;

Fig. 3 is a top plan;

Fig. 4 is an end elevation.

In the accompanying drawing, the numeral 1 indicates a portion of an arm of a 50 sewing machine, the needle bar appearing at 2 and carrying a needle 3, the needle 3 being held in place by means of a set screw 4, all as usual.

The embroidery attachment forming the 55 subject matter of this application is fashioned from a single length of resilient mate-

rial, preferably wire, the same being bent upon itself to fashion a lateral loop 5 comprising an upper arm 6 and a lower arm 7, the parts 6 and 7 being united by an integrally formed, spiral spring 8, constituting a means for aiding in compressing the lower arm. The upper arm 6 at one extremity is twisted upon itself to form a needle receiving eye 9, the constituent material of the eye 65 9 being continued to form an extension 10 embodying a rearwardly extended terminal 11 adapted to be engaged over the set screw 4 when the needle 3 is located in the eye 9. The upper arm 6 is bent upon itself to form 70 a forwardly presented elbow 16. The lower arm 7 is bent upon itself to fashion a forwardly presented elbow 12. This elbow 12, it is to be observed, does not lie in a plane at right angles to the axis of the eye 9 and 75 the axis of the needle 2, but lies in a plane which inclines upwardly and forwardly at an angle to the axis of the eye and the needle. The extremity of the lower arm 7 is formed into a forwardly extended projection 14, which slants upwardly and forwardly and is located approximately in a common plane with the upwardly slanting elbow 12, the projection 14 being bent upwardly and rearwardly at its extremity to 80 85 form a rounded, work guiding eye 15.

Owing to the fact that the projection 14 and the elbow portion 12 of the lower arm 7 lie in a rearwardly and downwardly slanting plane, the work may be operated on 90 readily, without the danger of catching on the attachment forming the subject matter of this application. Since the projection 14 is bent rearwardly and upwardly to form 95 the rounded end 15, a catching of the material is further avoided.

Since the arms 6 and 7 are fashioned respectively into the forwardly presented elbows 16 and 12, and owing to the general construction of the device, the work is at 100 all times visible, and the structure may be operated successfully in connection with embroidery rings.

In Fig. 1 of the drawings, the arrow A designates the general direction of advance 105 of the work.

Having thus described the invention, what is claimed is:—

An embroidery attachment fashioned from a single length of resilient wire, the same being bent upon itself to fashion a lateral loop comprising an upper arm and a lower arm,

the arms being united by an integrally formed spiral spring constituting a means for aiding in compressing the lower arm, the upper arm at one extremity being twisted 5 upon itself to form a needle receiving eye, the constituent material of the eye being extended to form an extension disposed at an acute angle to the upper arm and embodying a rearwardly extended terminal adapted 10 to be engaged over the screw of a needle bar, the upper arm being bent upon itself to form a forwardly presented elbow, and the lower arm being bent upon itself to fashion a forwardly presented elbow, the angle in the 15 elbow of the lower arm being more acute than the angle in the elbow of the upper arm, and the angle in the elbow of the upper arm lying to the rear of the angle in the

elbow of the lower arm, the elbow in the lower arm lying in a plane which is inclined 20 upwardly and forwardly at an angle to the axis of the eye, the extremity of the lower arm being formed into a free-ended forwardly prolonged projection bent forwardly and upwardly and is located approximately 25 in a common plane with the elbow of the lower arm, the projection having a free forward end which is bent upwardly and backwardly to form a work-guiding eye.

In testimony that I claim the foregoing as 30 my own, I have hereto affixed my signature in the presence of two witnesses.

LUCIUS M. TYNES.
